(57) **CLAIM**

The ornamental design for an element for positioning a resonant set of a compressor, as shown and described.

DESCRIPTION

FIG. 1 is a top perspective view of an element for positioning a resonant set of a compressor;

FIG. 2 is a front plan view thereof;

FIG. 3 is a rear plan view thereof; and,

FIG. 4 is a right side elevational view thereof, the left side elevational view being a mirror image.
